UNITED STATES PATENT OFFICE.

FRANZ BURGER AND HENRY M. WILLIAMS, OF FORT WAYNE, INDIANA; SAID BURGER ASSIGNOR OF ONE-HALF OF HIS RIGHT TO SAID WILLIAMS.

STEAM-BOILER.

SPECIFICATION forming part of Letters Patent No. 767,923, dated August 16, 1904.

Application filed December 17, 1902. Serial No. 135,627. (No model.)

To all whom it may concern:

Be it known that we, FRANZ BURGER and HENRY M. WILLIAMS, both citizens of the United States, residing at Fort Wayne, in the county of Allen and State of Indiana, have invented certain new and useful Improvements in Steam-Boilers, of which the following is a specification.

This invention relates to steam-boilers, and particularly to means for directing and controlling the passage of the products of combustion over the heating-surfaces of the boiler.

The invention will be fully described hereinafter, reference being had to the accompanying drawings, in which—

Figure 1 is a sectional side elevation of a boiler embodying our present invention, and Fig. 2 is a vertical transverse section.

The boiler consists of two outer semicylindrical shells A and B, connected together at their longitudinal edges at C in any suitable manner, and two similar but smaller inner shells *a* and *b*, connected together at their longitudinal edges at *c*, and the space between these inner and outer shells forms the steam and water spaces of the boiler and the space inclosed by the inner shells forms the fire-box or furnace of the boiler. The lower portions of the inner and outer shells are cut away to form a longitudinal slot in which are placed grate-bars for supporting fuel, as indicated by 3. An opening is cut in the top of the outer shell to afford communication with the usual steam-dome L. The outside shell is inclosed by a jacket I, a space being left between them, and this casing has connected to it an upwardly-extending casing J, which surrounds the steam-dome with a space between them, and the upper end of the casing J is contracted

40 to form a discharge-nozzle K, through which the products of combustion finally escape to the atmosphere. The casing I is provided with a longitudinal slot *i*, which is closed by a series of hinged flaps N. Preferably there will be a series of flaps N hinged to each edge of the slot *i* and normally inclining toward each other to meet at their free edges; but obviously flaps may be hinged to one edge only

of the slot and lie flat across the slot. These flaps will extend nearly from end to end of 50 casing or jacket I, except within the area of the casing J. There will thus always be a limited free opening around the dome L for the escape of the products of combustion. The slot *i* and flaps N are covered by casings O, 55 which communicate at one end with the casing J and are closed at their other ends, and these casings O form conduits through which products of combustion passing the flaps N are conveyed to the casing J. 60

Within the furnace and extending longitudinally on each side of the grate-bars or grating are two guard-walls H, made of fire-resisting material, and the coal or fragments of incombustible material will be confined between 65 these walls. A space will be left between each wall H and the opposing side of the furnace, and from this space a series of short inclined tubes G lead through the water-space of the boiler to the space between the outer shell of 70 the boiler and the jacket I, and through these tubes all the products of combustion must pass to the space between the jacket and boiler.

To supply the necessary air to the furnace, we preferably employ a forced draft, and for 75 this purpose a series of pipes 20 are supported beneath the grating and provided with nozzles through which air may be forced by any approved means. This forced draft may also be supplemented by an induced draft, and for 80 this purpose we may employ a pipe M, leading to the nozzle K, and air or steam may be forced through this pipe to create the induced draft. Preferably the pipe M will be provided with a controlling-valve, as indicated 85 by *m*.

Such being the preferred form of construction, the operation is as follows: The products of combustion generated in the furnace will first ascend to the top of the furnace and then 90 descend to the spaces between the walls H and the sides of the furnace, from whence they will pass through the tubes G into the space between the jacket I and the boiler. If only a light draft is being used, the flaps N 95 will open only slightly and the gases will es-

- cape slowly and will therefore be in contact with the boiler for a considerable period, thus enabling the boiler-shells to absorb more of their heat.
- 5 It is obvious that by controlling the draft the escape of the products of combustion from the nozzle K can be controlled, for the extent to which the flaps N will open will be automatically controlled by the force of the draft.
- 10 Each flap N may have a lug n, adapted to engage the casing I to prevent the flaps from opening too far or from swinging over onto the casing, or any other means may be employed for this purpose.
- 15 Without limiting ourselves to the precise construction illustrated and described, we claim—
1. The combination with a longitudinal boiler and its furnace, of a jacket inclosing 20 said boiler to leave a space between them, said jacket having a longitudinal slot in its top, hinged flaps normally closing said slot and conduits for conveying the products of combustion from the furnace to said space, substantially as set forth.
2. The combination with a longitudinal boiler and its furnace, of a jacket inclosing 25 said boiler to leave a space between them, said jacket having a longitudinal slot in its top, hinged flaps normally closing said slot, and tubes leading from the lower part of the furnace through the water-space of the boiler to the said space between the boiler and jacket, substantially as set forth.
3. The combination with a boiler and its 30 furnace, of a jacket inclosing the boiler to
- leave a space between them and having a longitudinal slot in its top, hinged flaps normally closing said slot, a casing inclosing said slot and flaps and having a restricted discharge-opening, and conduits for conveying the products of combustion from the furnace to the space between the boiler and casing, substantially as set forth. 40
4. The combination with a boiler and its 45 furnace, of a jacket inclosing said boiler to leave a space between them and having a longitudinal slot in its top, hinged flaps normally closing said slot, means to limit the opening movement of the flaps, and conduits for conveying the products of combustion from the furnace to the said space, substantially as set forth. 50
5. The combination with a boiler and its 55 furnace, of a jacket inclosing the boiler to leave a space between them and having a longitudinally-extending slot in its top, hinged flaps normally closing said slot, a casing inclosing said slot and flaps and having a restricted discharge-opening, conduits for conveying the products of combustion from the furnace to the said space, and means for creating a draft through the furnace, said space and the said casing, substantially as set forth. 60
- In testimony whereof we have signed our 65 names to this specification in the presence of two subscribing witnesses.
